UPPER STRETCHING AND HEEL SEAT
LASTING MACHINE

Jacob S. Kamborian, 133 Forest Ave., West Newton, Mass., and Henry v. d. Benken, West Roxbury, Mass.; said Benken assignor to said Kamborian
Filed May 2, 1961, Ser. No. 197,156
44 Claims. (Cl. 12—8.8)

In Patent No. 3,144,670, granted August 18, 1964, there is disclosed a method of counter molding and heel seat lasting that includes inserting a counter that has been heated to render it flaccid in a pocket at the heel end of an upper, mounting the upper and an insole on a last, applying pulling forces to the toe and forepart portions of the upper to stretch it tightly on the last and initiate the molding of the counter to the shape of the last, clamping the upper to the last at the heel end of the last to complete the molding operation and wiping the margin of the upper and counter against the insole to thereby last the heel of the shoe and adhesively bond the upper margin to the insole through the counter.

The instant invention comprises a pneumatically controlled automatically operated machine for carrying out the above referred to method. In addition, the machine has utility in efficiently lasting shoes without at the same time molding the counters.

The machine includes a post that is pivotally mounted on the piston rod of an air operated motor. An air operated motor is connected to the post to swing it toward and away from a heel seat lasting unit. A last support is located at the upper end of the post for supporting bottom-up a last having a shoe upper and insole thereon with the heel of the last facing the heel seat lasting unit. An upper tensioning unit is mounted on the post. The upper tensioning unit includes a front pincers for gripping the toe of the upper margin and a pair of side pincers for gripping the forepart portions of the upper margin. Air operated motors are provided to close the pincers jaws on the upper, to move the pincers in unison forwardly of the post and to raise the pincers upwardly of the post. The upper tensioning unit is slidably mounted on a pair of parallel bars extending forwardly of the post and air operated motors are provided to move the upper tensioning unit forwardly on the bars and to adjust the position of the unit on the bars. The last support at the upper end of the post comprises a last pin insertable into the last pin hole of a last and a shiftably mounted last supporting plate.

The heel seat lasting unit is mounted on a plate and the plate is slidably mounted in the frame and is connected to an air operated motor so that it may be shifted, after the shoe and last have been swung on the post adjacent thereto, from a relatively remote out-of-the-way position to a working position proximate to the shoe and last. A hold-down unit, comprising a hold-down foot, is located adjacent the lasting unit with the foot extending downwardly in front of the lasting unit. The lasting unit includes a U-shaped heel clamping pad that is driven by an air operated motor to bear against the heel of the last and upper. Auxiliary, air operated, presser members are provided to bear against the exterior of the clamping pad after the pad has been brought to bear against the last and upper. A pair of wipers are mounted above the clamping pad and are connected to an air operated motor to move them in a compound path that enables the wipers to move across the insole in directions substantially radial to the curvature of the last. An air operated motor is connected to the hold-down foot to raise it upwardly from a position where the foot is located slightly below the bottoms of the wipers.

A pedal operated pneumatic control system is provided

that is connected to the several air motors. The system is so arranged that a full depression of the pedal automatically causes the three pincers to grip the toe and forepart portions of the upper margin, the upper tensioning unit and the pincers carried by it to move forwardly on the parallel bars, the post to swing to a position adjacent the heel seat lasting unit, the post to rise upwardly to clamp the last and shoe between the last support and the hold-down foot, the pincers to rise in unison, the heel seat lasting to move from its out-of-the-way position to its working position, the heel clamping pad to move against the last and upper, the presser members to bear against the heel clamping pad, the wipers to move forwardly to last the shoe, and the hold-down foot to rise during the forward movement of the wipers. An arrangement is provided whereby a partial release of the pedal causes the machine to stop its cycle and a further full depression causes the machine to resume its cycle.

Reference is now made to the accompanying drawings 20 wherein:

FIG. 1 is a side elevation view of the machine;

FIG. 2 is an elevation view of the upper part of the machine drawn to a larger scale;

FIG. 3 is a front elevation view corresponding to 25 FIG. 2;

FIG. 4 is a view of the last supporting post;

FIG. 5 is a view taken along the line 5—5 of FIG. 4;

FIG. 6 is a view of a swivel block used to connect the upper tensioning unit to the last supporting post;

FIG. 7 is a view taken along the line 7—7 of FIG. 6;

FIG. 8 is a detail of the last supporting means;

FIG. 9 is a view taken along the line 9—9 of FIG. 8;

FIG. 10 is a side view of the upper tensioning unit;

FIG. 11 is a front view of the upper tensioning unit;

FIG. 12 is a top plan view of the upper tensioning unit;

FIG. 13 is a detail of the side pincers of the upper tensioning unit;

FIG. 14 is a detail of the front pincers of the upper tensioning unit;

FIG. 15 is a detail of the mechanism for adjusting the upper tensioning unit along the bars on which it is slidably mounted;

FIG. 16 is a section taken along the line 16—16 of 45 FIG. 15;

FIG. 17 is a detail of the upper tensioning unit;

FIG. 18 is a view taken along the line 18—18 of FIG. 17;

FIG. 19 is a view of the mechanism for swinging the 50 last supporting post;

FIG. 20 is a view taken along the line 20—20 of FIG. 19;

FIG. 21 is a detail of the mechanism for moving the heel seat lasting unit from its out-of-the-way position to its working position;

FIG. 22 is a view taken along the line 22—22 of FIG. 21;

FIG. 23 is a detail, partly in section, of the heel seat lasting unit and the hold-down unit;

FIG. 24 is a vertical section through the heel seat lasting unit;

FIG. 25 is a plan view of the heel clamping means;

FIG. 26 is a section taken along the line 26—26 of FIG. 25;

FIG. 27 is a side elevation of the heel clamping means;

FIG. 28 is a plan view of the wiping means;

FIG. 29 is a side elevation of the hold-down unit;

FIG. 30 is a view taken along the line 30—30 of FIG. 29;

FIG. 31 is a detail of an auxiliary presser member;

FIG. 32 is a showing of the pedal and pilot valve used to control the operation of the machine;

FIG. 33 is a section of a sequence valve;

FIG. 34 is a schematic representation of a pilot valve and the motors for moving the upper tensioning unit;

FIG. 35 is a section of the pilot valve shown in FIG. 32;

FIG. 36 is a schematic representation of the air control system of the machine;

FIG. 37A is a plan view of the shoe and last after they have been placed in the machine and the upper has been gripped by the front and side pincers;

FIG. 37B is a view taken along the line 37B—37B 10 of FIG. 37A;

FIG. 38 is a showing of the shoe and last after the shoe has been brought to bear against the hold-down foot;

FIG. 39 is a plan view of the shoe as it is about to be clamped by the heel clamping pad;

FIG. 40 is a section showing the shoe after it has been clamped by the heel clamping pad;

FIG. 41A is an elevation in section showing the heel portion of the shoe and last at the completion of the machine cycle; and

FIG. 41B is a view taken along the line 41B—41B 20 of FIG. 41A.

Referring to FIGS. 1 through 5, the machine comprises a frame 10 having an inclined plate 12. An air operated motor 14, mounted on the plate 12 has a piston rod 16 extending upwardly therefrom that is vertically guided in a guide bearing 18 secured to the frame. A post 20 is pivotally secured to the piston rod 16 by a pivot 22. A rod 24 is received in a socket in the upper end of the post 20. The rod 24 has a collar 26 slidably thereon, and a shaft 28 is threaded into the collar 26. The shaft 28 is rotatably mounted in the post 20 and has a pinion 30 at its lower end that is geared to a worm gear 32. The worm gear 32 is connected by means that include a universal coupling 34 and an endless chain 36 (FIG. 1) to a wheel 38, whereby rotation of the wheel 38 raises or lowers the collar 26 on the rod 24. A sleeve 39 is slidably mounted on the rod 24 and rests on the collar 26. A swivel block 40 (FIGS. 6 and 7) is pivotally mounted on the sleeve 39 for swinging movement about the axis of the sleeve with the bottom of the block 40 resting on the collar 26, and a snap ring 42 in the sleeve 39 engaging the top of the block 40. Thus raising or lowering the collar 26 also raises or lowers the block 40.

A last pin holder 44 or 44¹ (FIGS. 8 and 9) is mounted at the upper end of the rod 24. The last pin holder has a prong 46 depending therefrom that is seated in a hollow at the upper end of the rod 24 and is connected thereto by a bolt 48. A last pin 50 is fastened in an axial hole 51 in the last pin holder and projects upwardly thereof. The last pin holder 44 or 44¹ has a concave groove 52 in its upper surface that receives a last supporting plate 54, the plate 54 having a convex lower surface complementary to surface of the groove 52, a flat upper surface 56 and a hole 58 through which the last pin 50 extends. The plate 54 is of narrower width than the groove 52 and the hole 58 has a larger diameter than the pin 50 for a purpose that will be explained below.

The swivel block 40 has a groove 60 on each side thereof, and parallel bars 62 are rigidly mounted in each groove 60 to extend forwardly of the block 40. An air operated motor 64 is pivotally connected to each bar 62 to extend forwardly of the block 40. The piston rods 66 of the motors 64 are rigidly connected to a head 67 forming part of an upper tensioning unit 68 that is slidably mounted on the bars 62.

From the foregoing it can be seen that the post 20 and rod 24 act as a mount for both the last supporting members 50, 54 and 44 or 44¹ and the upper tensioning unit 68.

Referring to FIGS. 10 through 18, the unit 68 has a guideway 70 at its forward end for guiding a toe post 72 up and down with respect to the unit 68 (see FIGS. 17 and 18). The post 72 has a toe rest roller 74 rotatably mounted at its upper end and a screw 76 threaded

into its lower end. The screw 76 is rotatably mounted in a bearing 78 that is rigidly mounted on the unit 68 and is connected by an endless belt 80 to a wheel 82 rotatably mounted in the unit 68, whereby rotation of the wheel 82 raises or lowers the toe rest 74 relative to the unit 68.

An air operated motor 84 mounted on the unit 68 has a piston rod 86 that is connected to a T-bar 88 that is slidably mounted for up-and-down movement in the unit 68. At the top of the upright limb 90 of the T-bar, there is mounted a front pincers bracket 92 (FIGS. 13 and 14). The bracket 92 has a pair of upright slots 94 which receive studs 96 that are threaded into the T-bar 88 to thereby adjustably mount the bracket 92 on the T-bar. A pincers 98 is mounted on the bracket 92. The pincers 98 comprises a stationary pincers jaw 100 rigidly connected to the bracket 92 and a movable pincers jaw 102 swingably mounted on the bracket 92. An air operated motor 104, mounted on the bracket 92, has a piston rod 106 engageable with the pincers jaw 102, the latter member being normally urged to open position by a spring 108. The bracket 92 has a rib 110, on whose bottom there is a groove 112 that partially envelope a shaft 114. A pair of collars 116 are pinned to the shaft 114 on opposite sides of the rib 110. The shaft has right and left hand threads at its opposite ends whereby it is screwed into bosses 118 that are secured to side pincers brackets 120. A wheel 121 is secured to one of the ends of the shaft 114. The brackets 120, which are slidably mounted on the prone legs 122 of the T-bar 88, support side pincers 124. Each side pincers 124 comprises a fixed jaw 126 rigidly connected to a bracket 120 and a movable jaw 128 pivotally mounted on a bracket 120 by a pivot 130 and pivotally connected to the piston rod 132 of an air operated motor 134 that is secured to an extension 136 on each bracket 120.

A shelf 138 is secured to one of the bars 62 (see FIGS. 15 and 16). A bracket 140 is slidably mounted on the shelf 138 and can be locked in a desired position on the shelf by swinging a handle 142 that is pivoted to the bracket 140 by a rod 143 that is rigidly connected to the handle and pivotally mounted in the bracket. The handle includes a cam 144 whose center is eccentric with respect to the rod 143 and thereby engages the shelf 138 to lock the bracket 140 in place upon swinging of the handle. The bracket 140 has a spring return air operated pilot motor 146 mounted thereon. The piston rod 148 of the motor 146 is engageable with the valve spool 149 of a pilot valve 151 mounted on the upper tensioning unit 68.

The post 20 is pivotally connected to the legs 150 of a forked pitman 152 that straddles the post (see FIGS. 19 and 20). The pitman 152 is pivotally and eccentrically connected to a crank 154. The crank 154 is connected to a shaft 156 which in turn is pivotally mounted in the frame 10. The shaft 156 has a gear 158 secured thereto that is in mesh with a rack 160 mounted on a D-shaped rack support 162, the rack being slidably guided in gibs 163 located in the frame 10. An air operated motor 164, mounted in the frame 10, has a piston rod 166 connected to the rack frame 162 to effect the vertical movement of the rack 160 and hence swinging movement of the post 20 about the pivot 22. A valve 168 is mounted in the frame 10 and has a valve spool engageable by lugs 170 and 172 at either extremity of movement of the rack frame 162, the lugs being adjustably mounted in the rack frame. A shock absorber 174 is interposed between the frame 10 and the rack 160 to eliminate chattering and ensure a smooth operation when the rack is caused to move upwardly or downwardly in the frame.

A heel seat lasting unit 176 is mounted in the frame 10 rearwardly of the upper tensioning unit 68. Referring to FIGS. 21 through 31, the unit 176 comprises a main slide plate 178 slidably mounted for forward and rearward movement on gibs 180 in the frame 10 (see FIG.

24). A block 182 is secured to plate 178 and is slidable in a slot 184 formed in a table 186, which table forms a part of the frame 10. A floating actuator 188 is secured to the block 182. The actuator 188 comprises a bar 190 depending from and rigid with the block 182. An air operated motor 192 is pivoted to the bar 190 and has a piston rod 194 extending upwardly therefrom. A pair of toggle links 196 and 198 are pivoted at their adjoining ends to the piston rod 194, and are respectively pivoted at their opposite ends to the bar 190 and a block 199 taking the form of a nut. A screw 200 is rotatably mounted in hangers 202 and 204 depending from the table 186, extends through a clearance opening 206 in the bar 190 and is threaded into the nut 199. The screw 200 is connected through a gear train 208 and a shaft 210 to a wheel 211. Thus, rotation of the wheel 211 causes the nut 199 to move axially of the screw 200 and causes the floating actuator 188, the block 182, the main slide plate 178 and the members carried thereby to move forwardly and rearwardly in the frame. Actuation of the motor 192 to open or close the toggle linkage formed by the members 194, 196 and 198 will also cause the main slide plate 178 and the members carried thereby to move forwardly and rearwardly in the frame.

A pair of air actuated motors 212 are mounted on the plate 178. Each motor 212 has a piston rod 214 that is pivotally connected to a lever 216 by a pivot 218. The levers 216 have legs 220 extending toward each other from the pivots 218 and legs 222 extending forwardly and divergently from the pivots 218. The legs 220 are pivotally connected by pivots 224 to a slide 226. A pair of tension springs 228 and 230 are connected at their opposite ends to arms 232 that are fixed to the legs 220. The springs force the levers 216 about the pivots 218 to the position shown in FIG. 25 where the contiguous faces of the legs 220 abut each other. The slide 226 is slidably mounted in gibs 234 mounted on the plate 178. The lever legs 222 have studs 236 adjustably mounted in their extremities, and the studs 236 are affixed to the ends of a U-shaped heel clamping pad 238 made of a flexible material such as leather. A pair of sprocket chains 240 are wrapped around the outer periphery of the pad 238. Each chain 240 is anchored at one end to a stud 226. The slide 236 has a projection 242 at its forward end (FIG. 26) having a slot 244 in which the other end of each chain 240 is received. A pair of pins 246 mounted in the projection 242 extend across the slot 244 and through the ends of the chains 240 remote from the studs 236. A pair of spring return air actuated motors 248 are mounted in each of the lever legs 222 (FIGS. 25 and 31). The motors 248 have pistons 250 extending toward the pad 238 below the chains 240. A presser member 252 is affixed to each piston 250.

A bridge 254 is anchored at its ends to the sides of the main slide plate 178 and extends thereover. An air operated motor 256 is secured to a rib 258 at the rear of the main slide plate 178. The piston rod 260 of the motor 256 has a rack 262 thereon that is in mesh with a gear 264 rotatably mounted beneath the bridge 254 on a pin 266 fixed in the bridge. A wiper supporting slide plate 268 is slidably supported on gibs 270 in the frame (FIGS. 24 and 28). The plate 268 has a slot 272 extending transverse to the rack 262 which receives an eccentrically mounted crank pin 274 depending from the gear 264. The piston 260 has an enlargement 276 to which are pivoted the ends of links 278. The opposite ends of the links 278 are pivoted to wiper cams 280, and a wiper 282 is mounted in each wiper cam. The wiper cams 280 have curved cam slots 284 with a center of curvature at the point where the wipers diverge from each other, indicated by numeral 286 in FIG. 28. The wiper cams rest on the plate 268, and the plate 268 has rollers 288 extending upwardly therefrom into the cam slots 284. A valve actuating lug 289 mounted on the piston rod 260 is en-

gageable with the valve spool 290 of a valve 292 that depends from the bridge 254.

A hold-down unit 294 is mounted on a frame cover 296 located above the plates 178 and 268 and the wiper cams 280. The unit 294 comprises a lever 298 pivoted to a clevis 299 on the cover 296 by a pivot 300, see FIGS. 23, 29 and 30. A link 302 is pivoted to the cover 296 below the pivot 300, and both the lever 298 and the link 302 are pivotally connected to a hold-down foot 304. The lever 298, link 302 and foot 304 thus form a parallel linkage mechanism whereby counterclockwise movement of the lever (FIG. 29) imparts a substantially rectilinear downward movement to the foot 304 and clockwise movement of the lever 298 imparts a substantially rectilinear upward movement to the foot 304.

A pin 306 is rotatably mounted in the cover 296 rearwardly of the pivot 300, and a roller 308 is affixed to the pin 306. A roller 310 is rotatably mounted in a clevis 312 that is slidably mounted for up and down movement at the rear end of the lever 298 opposite the roller 308. A screw 314 bears against the upper surface of the clevis 312 to limit the upward movement of the clevis 312 in the lever 298.

An air operated spring return motor 316 is secured to the cover 296. The piston rod 318 of the motor 316 has a cam 320 secured thereto that is interposed between the rollers 308 and 310. A tension spring 322 extending from the pin 306 to a pin 324 fixed to the lever 298 urges the roller 310 against the cam 320. The cam 320 has a high portion 326 that is normally interposed between the rollers 308, 310. The actuation of the motor 316 to bring a low portion 328 of the cam between the rollers will cause the spring 322 to move the roller 310, which acts as a cam follower, downwardly against the cam portion 328, swing the lever 298 clockwise, and thereby raise the hold-down foot 304, for a purpose that is explained below.

A plate 330 is secured to the cover 296 (see FIG. 3). The plate 330 has indicia thereon representing various shoe sizes. A gauge bar 332 has an end located above the plate 330 and is connected at its other end to the bridge 254 (see FIG. 23).

As stated above, although the apparatus of the instant invention can be used to assemble an upper on a last and heel seat last the upper onto the insole, it has particular utility in carrying out the method disclosed in the above cited Patent No. 3,144,670, granted August 18, 1964. In the referred to method, a flaccid counter coated on both of its surfaces with adhesive is inserted in a pocket formed between an upper and a liner at the heel end of the upper, the upper is draped about the last, tensioning forces are applied at the toe end of the upper to wrap the upper about the heel end of the last and initiate the molding of the counter to the shape of the last, the last is moved to a heel seat lasting position and forced upwardly against a hold-down, upward tensioning forces are applied at the toe end of the upper to assemble the upper on the last, a clamping force is applied at the heel of the last to maintain the upper stationary on the last and to complete the molding of the counter to the shape of the last, and the margins of the upper and counter are wiped down onto an insole located on the bottom of the last to thereby unite the lasted margin of the upper to the insole by adhesively bonding the counter to the upper and insole.

In setting up the machine for a particular size of last, the knobs 334 (FIG. 25), which are threaded onto the studs 236 are rotated to move the studs toward or away from each other to thereby adjust the contour of the clamping pad 238. The wheel 121 is rotated to move the side pincers 124 toward or away from each other. The wheel 38 is rotated to raise or lower the upper tensioning unit 68 with respect to the rod 24 and the last pin 50 at the upper end of the rod 24. A last pin holder such as 44 or 44¹ having the appropriate heightwise dimension is inserted into the top of the rod 24. The heightwise dimen-

sion of the last pin holder used is dependent on the heightwise dimension of the last.

The screw 314 is rotated to raise or lower it in the lever 298. Since the spring 322 urges the rollers 308, 310 toward each other, the heightwise movement of the screw 314 causes a corresponding heightwise movement of the clevis 312 and a raising or lowering of the hold-down foot 304. The hold-down foot should be positioned below the bottoms of the wipers 282 an amount that is dependent on the thickness of the upper margin and the counter.

The wheel 211 is rotated to move the heel seat lasting unit 176 forwardly or rearwardly in the frame 10.

The position of the bracket 140 on the shelf 138 is adjusted to correspondingly adjust the position of the upper tensioning unit 68 on the bars 62. This is accomplished in the following manner. The pilot valve 151, as shown in FIG. 34, has a centrally located air inlet port 336 and vent ports 338 and 340 on opposite sides of the port 336. The valve spool 149 has a knob 342 at one end and a compression spring 344 is interposed between the knob 342 and the valve housing 346 to yieldably urge the valve spool against the aforementioned piston rod 148 (FIG. 15). The valve has a port 348 that is connected to one end of the motors 64 and a port 350 that is connected to the other end of the motors 64. Lands 352 and 354 on the valve spool 149 normally block the ports 348 and 350. Air normally enters the inlet line 356 of the motor 146 to extend the piston rod 148 out of the motor against the pressure of the spring 358 in the motor. Operation of the handle 142 to move the piston rod 148 away from the knob 342 causes the spring 344 to push the valve spool rightwardly (FIGS. 15 and 34) and follow the piston rod 148 and thus provide an air path between the valve ports 336 and 350 to thereby actuate the motors 64 to move the upper tensioning unit 68 along the bars 62 away from the block 40 until the piston rod 148 again moves the valve spool 149 to the FIG. 34 position. Operation of the handle 142 to move the piston rod 148 leftwardly against the knob 342 moves the knob leftwardly in the valve housing to provide an air path between the ports 336 and 348 to actuate the motors 64 to move the upper tensioning unit 68 along the bars 62 towards the block 40 until the piston rod 148 stops its leftward movement and the valve spool 149 reassumes its FIG. 34 position. Thus, movement of the bracket 140 on the shelf 138 in a given direction causes the upper tensioning unit 68 to move along the bars 62 a corresponding amount in the same direction.

The wheel 82 is rotated to raise or lower the toe rest roller 74.

The rack 160 normally has its lower end in mesh with the pinion 158 so that the post 20 and the upper tensioning unit 68 are swung away from the heel seat lasting unit 176 and the hold-down unit 294 as shown in FIG. 1, and the toggle linkage of the floating actuator 188 is normally in the FIG. 21 position so that the heel seat lasting unit 176 is in a rearward position in the frame 10.

A last 358 is provided having an insole 360 mounted on its bottom and an upper 362 draped thereon. A liner 364 is secured to the heel of the upper to engage the heel of the last, and a counter 366 is located in the pocket formed between the upper and the liner. The last is placed bottom-up on the last supporting plate 54 with the pin 50 entering the conventional last pin hole in the last. The toe portion of the upper and last is supported on the toe roller 74, the toe end of the upper margin is inserted between the jaws of the pincers 98, and the forepart portions of the upper margin are inserted between the jaws of the side pincers 124. At this time the upper end of the liner 364 is substantially level with the insole 360 and the upper margins of the counter 366 and upper 362 at the heel end of the last extend above the insole 360 as indicated in FIGS. 37A and 37B.

An automatically operated pneumatic control system is provided to cause the machine to go through a cycle. The system is actuated by a foot controlled pedal 368 (FIGS. 1 and 32) that is pivoted to the frame 10 by a pivot 370

and is urged clockwise about the pivot by a counterweight 372. A stop screw 374, threaded into a pedal extension 369 that extends rightwardly of the pivot 370, is engageable with a bar 376 of the frame 10 to limit the amount the pedal may move clockwise under the influence of the counterweight. A pilot valve 378 is mounted above the lever extension 369. As shown in FIG. 35, the valve 378 has an air inlet port 380 located centrally of the valve housing 382 and air vent ports 384 and 386 located adjacent the opposite ends of the housing 382. A port 388, located between the ports 380 and 384, is connected through a line 390 to the working side of the pneumatic system, and a port 392, located between the ports 380 and 386, is connected through a line 394 to the venting side of the pneumatic system. The spool 396 of the valve 378 has lands 398 and 400 which block the ports 388 and 392 when the valve spool is in neutral position. The valve spool is normally urged downwardly by a compression spring 402 interposed between the valve housing 382 and a knob 404 on the end of the spool to bring the knob to bear against the pedal extension 369. In this position, an air passage is open between an air inlet line 406, that is connected to a source of air pressure (not shown), and the line 394 leading to the venting side of the system through the ports 380 and 392. At the same time air from the working side of the system escapes to atmosphere through the line 390 and ports 388 and 384. A movement of the valve spool 396 upwardly an amount sufficient to provide an air passage between the ports 380 and 388 causes air under pressure to enter the working side of the system through the port 388 and permits air on the venting side of the system to pass to atmosphere through the line 394 and the ports 392 and 386.

The valve spool 396 has a head 412 at its upper end that is engageable with the valve housing 382 to limit the downward movement of the valve spool in the housing. A stud 408 is slidably mounted in alignment with the valve spool 396 in a bracket 410 above the valve 378. The stud has an enlarged head 412 at its lower end that acts as a stop, and a pair of lock nuts 414 at its upper end and above the bracket 410. A compression spring 416 interposed between the bracket 410 and the head 412 yieldably urges the stud 408 downwardly to a position where the lower lock nut 414 engages the bracket 410. When the operator depresses the pedal 368 to raise the valve spool 396 he will feel no resistance to the pressure exerted by the head 412 of the stud 408. At this position of the valve spool the pneumatic system is in neutral position and all the elements controlled by the system remain in the position they were in prior to the placing of the valve in neutral position. An application of increased pressure by the operator on the pedal 368 to overcome the force of the spring 416 will place the valve spool in position to connect the working side of the system to the source of air pressure and operate the various motors controlled by the system in the below described sequence. At any time during the operation of the machine cycle the operator may stop the machine parts in a particular position by releasing his pressure on the pedal 368 until he no longer feels the pressure of the spring 416 and thus bring the valve spool 396 into neutral position.

The control system includes a plurality of sequence valves such as is illustrated in FIG. 33. The sequence valve has an inlet port 420 and an outlet port 422. The inlet port 420 is in communication with a poppet 424 mounted in a recess 425 and having a land 426 and a stem 428 extending downwardly of the land into a cavity 430, there being clearance between the stem 428 and the cavity 430. A sealing ring 432 mounted on the stem 428 bears against the top of the cavity 430. The stem 428 is yieldably urged into the cavity 430 by a relatively weak spring 434 that bears against the poppet land 426. The outlet port 422 is in communication with a poppet 436 mounted in a recess 438. The poppet 436 has a land 440

and a stem 442 extending into a cavity 444 with clearance between the stem 442 and the cavity 444. A sealing ring 446 mounted on the stem 442 bears against the bottom of the cavity 444. The stem 442 is yieldably urged into the cavity 444 by a relatively strong spring 448 that bears against the poppet land 440.

Air under pressure entering the inlet port 420 will pass through the recess 425 and into the cavity 444 to force the poppet 436 downwardly against the force of the spring 448 to enable it to bypass the sealing ring 446 and exit from the port 422. This air cannot directly enter the cavity 430 because the way is blocked by the sealing ring 432. Since the spring 448 is relatively strong the air will take a path of lesser resistance, if one is available, before passing through the sequence valve.

Air entering the port 422 will pass through the recess 438 and into the cavity 430 to force the poppet 424 upwardly against the force of the spring 434 to enable it to bypass the sealing ring 432 and exit from the port 420. This air cannot directly enter the cavity 444 because the way is blocked by the sealing ring 446. Since the spring 434 is relatively weak, the air passes from the port 422 to the port 420 with substantially no delay or time lag.

After the last and shoe have been positioned in the machine in the manner described above, the pedal 368 is depressed an amount sufficient to overcome the force of the spring 416 and bring the valve 378 to a position where the air line 406 is in communication with the air line 390 and the working side of the pneumatic system. Referring to FIG. 36, where the air lines in the working side of the system are drawn solid and the air lines in the venting side of the system are drawn dotted, air pressure passes from line 390 to the motors 104 and 134 to actuate them to cause the front pincers 98 and the side pincers 124 to grip the margin of the upper as indicated in FIGS. 37A and 37B. If desired, additional pincers may be provided to engage the upper margin at the ball of the shoe. The additional pincers may be mounted to partake of the forward and heightwise movement of the pincers 98 and 124 described below. Alternatively, the pincers 124 may be mounted to engage the upper at the ball of the shoe. After the motors 104 and 134 have been actuated, the air passes through a sequence valve 450 to actuate a four way pilot valve 452. The actuation of the pilot valve 452 allows air to pass from a line 454, through the valve 452 and a line 456 into a three way pilot valve 458 to move the valve 458 from its *a* to its *b* position. Prior to the depression of the pedal 368 by the operator, air had flowed from the line 406, the valve 378, the line 394, a line 467, a line 526, the valve 458, the line 356 and a flow control valve 459 into the motor 146 to force the piston 462 of the motor leftwardly (FIG. 15) against a stop 464 thereby compressing the spring 358. Immediately after the depression of the pedal 368, the motors 104 and 134 were actuated causing air to vent out of the motors 104 through a line 461 and the valve 378. The air passing through the line 461 maintains the pressure against the piston 462 by passing through the valve 458 before the spring 358 can move the piston rightwardly (FIG. 15). The flow control valve 459 slows down the egress of air from the motor 146 sufficiently to allow this to take place. The movement of the valve 458 to its *b* position allows the air in the motor 146 to vent to atmosphere through the line 356, the valve 458, the line 460 and the valve 452. The spring 358 therefore moves the piston rod 148 rightwardly (FIG. 15) to actuate the valve 151 to cause air to enter the motors 64 through an air line 466, the valve 151 and an air line 468 in the manner described above. Actuation of the motors 64 causes the upper tensioning mechanism including the pincers 98 and 124 to move forwardly on the bars 62 to thereby horizontally stretch the upper in the direction of the toe of the last and cause a firm wrapping of the upper about the heel of the last and a tension force on the counter to start to mold it to the shape of the last.

Air pressure can now pass through the sequence valve

470 to actuate the three way valve 472 to allow air to pass through the lines 390 and 474, the valve 472 and lines 476 and 478 to the motor 164. The motor 164 is thus actuated to lower the piston rod 166 (FIG. 19) and the rack frame 162 to thereby swing the post 20 about the pivot 22 to a position where the shoe is adjacent to but not in engagement with the heel seat lasting unit 176 and the hold-down unit 294. In this position the post 20 is in alignment with the hold-down foot 304 but the insole 360 is below the bottom of the hold-down foot. In addition, in this position, the shoe upper and last are not in engagement with the heel clamping pad 238.

The lowering of the rack frame 162 causes the lug 170 to engage the three way valve 168 and actuate the valve to permit air to pass through the valve 168 and air line 479 to actuate a three way pilot valve 480. The actuation of the valve 480 causes air to pass through the valve 480 and through a quick exhaust valve 482 to the motor 14 to cause the motor 14 to raise the post 20 upwardly and thus raise the last and shoe upwardly until the insole 360 bears against the hold-down foot 304. In this position the shoe and last are clamped between the hold-down foot 304 and the last supporting plate 54, as indicated in FIG. 38, with the upwardly facing surface of the insole slightly below the top surface of the clamping pad 238 and the bottom surface of the wipers 282. The aforementioned mounting of the plate 54 on the last pin holder 44 or 441 and the oversize opening in the plate to accommodate the last pin 50 permits the plate to rock in the concave groove 52 and shift transversely of the groove to provide a maximum bearing surface of the plate against the last 358 when the post 20 is moved upwardly to force the last and shoe against the hold-down foot 304.

Concomitantly with the actuation of the motor 14 to raise the post 20, air pressure passes through a line 484 to a sequence valve 486. After the motor 14 is actuated, the sequence valve 486 is actuated to shift a pilot valve 488 to allow air to pass through the valve 488 to the motor 84. Actuation of the motor 84 raises the T-bar 88 to raise the pincers 98 and 124 to thereby apply an upward tension to the margin of the upper 362 at its toe and forepart portions to thereby stretch the upper tightly on the last and assemble it in proper position for the subsequent heel seat lasting operation. Since the last and shoe are clamped at this time between the foot 304 and the plate 54, upward movement of the pincers will not shift the last.

After the motor 84 has been actuated, air can pass from the valve 488 through the line 490 and through the sequence valve 492 to actuate the pilot valve 494. Actuation of the pilot valve 494 causes air to pass from the line 490 through the valve 494 to the motor 192 on the floating actuator 188 to thereby raise the piston rod 194 and straighten the toggle links 196 and 198. The straightening of the toggle links moves the block 182 and the heel seat lasting unit 176 carried thereby from its normal out of the way position to a position adjacent the shoe and last.

Air can now pass from the valve 494 through the sequence valve 496 to actuate the pilot valve 498. Actuation of the pilot valve 498 causes air to pass therethrough and through the lines 500 and 502 to the motors 212. Actuation of the motors 212 causes the piston rods 214 to move the levers 216 and the clamping pad 238 carried thereby toward the heel of the last with the slide 226 sliding in the gibs 234. During this movement the springs 228 and 230 maintain the lever legs 220 in abutting relation and the lever legs 222 in open position until the bight 504 engages the shoe as indicated in solid lines in FIG. 39. At this time the bight of the pad and the slide 226 can no longer move forwardly so that continued forward movement of the piston rods 214 causes the levers 216 to swing toward each other about the pivots 224 to cause the legs 506 of the pad to move toward each other and engage the shoe as indicated in dotted lines in FIG. 39. This arrangement provides for an initial contact of the pad

238 at the heel end of the shoe and then a progressive engagement of the pad along the sides of the shoe extending forwardly of the heel to ensure a smoothening out of any wrinkles there may be in the upper and a smooth, firm clamping of the upper against the last.

Air now passes through a sequence valve 503 to actuate a three way pilot valve 510 to allow air to pass through the valve 510 and a line 512 to the motors 248 to force the presser members 252 against the clamp pad 238 and thereby press the clamp pad against the shoe and last. As seen in FIG. 40, the presser members 252 engage the pad 238 towards the bottom of the pad opposite the portion of the last that curves inwardly to form a last portion having a relatively narrow width. The presser members 252 ensure that all of the clamp 238 bears against the last 358 to thereby hold the upper firmly in place during the subsequent lasting operation and to complete the molding of the counter 366 to the shape of the last.

Shortly after the actuation of the motors 248, air passes from the line 512 through a flow control valve 514 into the motor 256. Actuation of the motor 256 advances the piston rod 260, the rack 262 and the piston rod enlargement 276 to cause the wipers 282 to be moved from the dotted line position of FIG. 41B to the solid line position and wipe or fold the margin of the upper 362 and counter 366 down against the insole 360. The wiping pressure completes the molding of the counter and causes the counter, through the adhesive on its surfaces, to bond the wiped-in margin of the upper to the insole. The forward movement of the piston rod 260, through the links 278, causes the wipers 282 to move toward each other about the point 286. The forward movement of the piston rod 260, through the rack 262, the pinion 264, the slot 272 and the pin 274 also causes the plate 268 to move forwardly thereby providing a forward movement of the wipers as well as an inward movement about the point 286. Since the slot 272 extends normal to the path of movement of the piston rod 260, the movement of the slot from the rightward position of FIG. 28 to the leftward position indicated in phantom causes the plate 268 initially to move forwardly almost as fast as the piston rod 260 and then to gradually slow down, until, towards the end of the stroke of the piston rod, the plate has substantially no forward movement. The result of this is that initially, the wipers move forward with substantially no inward movement about the point 286, and at the end of the wiper stroke, the wipers move toward each other about the point 286 with very little forward movement. This produces a wiping action where the force created by the wipers in moving across the edge of the insole 360 at any given point is substantially radial to the curvature of the insole at that point.

During the forward stroke of the piston rod 260, the lug 289 actuates the three-way valve 292 to allow air to pass through the valve 292 to the motor 316. Actuation of the motor 316 moves the cam 320 forwardly to present the low cam portion 328 between the rollers 308, 310 and thus cause the raising of the hold-down foot 304 as indicated in FIG. 41A. The motor 14 now applies upward pressure by the last directly against the wipers to provide an overwiping and bedding pressure between the wipers and the wiped in margin of the upper during the latter part of the wiper stroke and also after the termination of the wiper stroke.

This concludes the working phase in the machine cycle. As stated above, the operator may, at any time during this phase, release his foot pressure on the pedal 368 an amount sufficient to bring the valve 378 into neutral position, in which event, the machine parts will maintain the position they have assumed at that particular time. This enables the operator to inspect the work anytime he desires during the working phase of the machine cycle, and then either resume the working phase by stepping down

harder on the pedal or return the machine to starting position by releasing the pedal.

After the working phase has been completed, the operator releases his foot from the pedal 368. This causes air pressure to go through the valve 378 and the lines 394 and 461 to the motors 104 and 134 to open the pincers 98 and 124 and release the upper margin at the toe and forepart portions. At the same time, air pressure passes through the line 461 to the motor 84 to actuate the motor 84 to lower the T-bar 88 and the pincers 98 and 124 to their initial position. At the same time air pressure goes from the valve 378 and a line 516 to the motors 212 to actuate the motors 212 to open the clamping pad 238. At the same time air passes through the line 516 to the motor 192 to return the heel seat lasting unit 176 to its original out of the way position. At the same time air passes through the line 520 to the valve 488 to return it to its original a position which permits air to be vented from the motor 84 through the valve 488. At the same time the valve 452 and the valve 458 are respectively caused by air pressure in a line 522 and the lines 467 and 524 to return to their original positions. The return of the valve 458 to its a position allows air pressure to pass through the line 526 into the motor 146 to move the piston 462 leftwardly (FIG. 15) against the pressure of the spring 358 to actuate the pilot valve 151 to operate the motors 64 to return the upper tensioning unit 68 to its original position on the bars 62. At the same time, air passing through a line 528 returns the valves 472 and 480 to their original positions.

Now a sequence valve 530 is actuated through a line 532 to actuate a pilot valve 534. Actuation of the valve 534 causes air to pass therethrough to the motor 14 to cause the motor 14 to lower the post 20 and thereby lower the last and shoe. At the same time air flows from the valve 534 to the motor 256 to actuate the motor 256 to retract the wipers 282. At the same time air flows to the valve 510 through a line 536 to return the valve 510 to its original position. The return of the valve 510 to its original position allows the air in the motors 248 to be vented through the line 512 and the valve 510 to atmosphere and to cause the springs in these motors to return them to their original positions.

The retraction of the wipers by the rearward movement of the piston rod 260 causes the lug 289 to release the valve spool 290 and return the valve 292 to its original position and thereby allow the spring in the motor 316 to retract the piston rod 318, return the high cam portion 326 between the rollers 308 and 310 and lower the hold-down foot 304 to its original position.

Air can now pass through a sequence valve 538 to actuate a three way pilot valve 540 to allow air to flow through the valve 540 and a line 542 to the motor 164 to cause the motor to raise the rack support 162 and thereby swing the post 20 away from the heel seat lasting unit 176 back to its original position. The raising of the rack support causes the lug 172 to move the valve 168 back to original position.

It should be understood that the present disclosure is for the purpose of illustration only and that this invention includes all modifications and equivalents which fall within the scope of the appended claims. Terms such as "heightwise," "forward," and "below" are merely indicative of the relative paths of movement and the positions of the machine parts and should be so construed.

We claim:

1. A heel seat lasting machine comprising: wiping means movable forwardly in a predetermined plane; a hold-down located forwardly of the wiping means; a mount; a shoe support, for supporting bottom-up a last having a shoe upper and insole thereon, located on the mount and positioned below the hold-down and forwardly of the wiping means; gripping means mounted on the mount for gripping the margin of the upper proximate to its toe end; means for moving the gripping means for

wardly of the shoe support to stretch the upper about the heel of the last; means for raising the shoe support together with the gripping means to clamp the last and shoe between the shoe support and hold-down; means for raising the gripping means upwardly of the shoe support to stretch the upper tightly on the last; and means to move the wiping means forwardly to wipe the heel portion of the upper margin down upon the insole.

2. A heel seat lasting machine comprising: wiping means movable forwardly in a predetermined plane; heel clamping means located below the wiping means; a hold-down, positioned forwardly of the wiping and clamping means, comprising a foot whose bottom is located slightly below the bottom of the wiping means; a mount; a shoe support located on the mount, for supporting bottom-up a last having a shoe upper and insole thereon, mounted for movement toward and away from the wiping means and heel clamping means; gripping means mounted on the mount for gripping the margin of the upper proximate to its toe end; means for moving the gripping means forwardly of the shoe support to stretch the upper about the last; means for moving the mount together with the shoe support from a position remote from the wiping and heel clamping means to a position adjacent thereto; means for raising the shoe support together with the gripping means to clamp the last and shoe between the shoe support and hold-down; means for raising the gripping means upwardly of the shoe support to stretch the upper tightly on the last; means to actuate the clamping means to clamp the heel portion of the upper against the last; and means to move the wiping means forwardly to wipe the heel portion of the upper margin down upon the insole.

3. A heel seat lasting machine comprising: wiping means movable forwardly in a predetermined plane; heel clamping means located below the wiping means; a hold-down, positioned forwardly of the wiping and clamping means, comprising a foot whose bottom is located slightly below the bottom of the wiping means; a mount pivotally mounted on a rod for swinging movement toward and away from the wiping means and heel clamping means; a shoe support, located on the mount for supporting bottom-up a last having a shoe upper and insole thereon; gripping means mounted on the mount for gripping the margin of the upper proximate to its toe end; means for moving the gripping means forwardly of the shoe support to stretch the upper about the last; means for swinging the mount together with the shoe support and gripping means about the rod from a position remote from the wiping and heel clamping means to a position adjacent thereto; means for raising the rod to thereby raise the shoe support and clamp the last and shoe between the shoe support and hold-down; means for raising the gripping means upwardly of the shoe support to stretch the upper tightly on the last; means to actuate the clamping means to clamp the heel portion of the upper against the last; and means to move the wiping means forwardly to wipe the upper margin down upon the insole.

4. A heel seat lasting machine comprising: a frame; a lasting unit slidably mounted in the frame for forward and rearward movement from an out-of-the-way position to a working position, said lasting unit comprising wiping means movable forwardly in a predetermined plane and heel clamping means located below the wiping means; a hold-down unit mounted in the frame, said hold-down unit comprising a hold-down foot whose bottom is normally located slightly below the bottom of the wiping means; a mount pivotally mounted on a rod for swinging movement toward and away from the lasting unit; a shoe support, located on the mount, for supporting bottom-up a last having a shoe upper and insole thereon; powered means connected to said rod to effect heightwise movement of the rod and of the shoe support; gripping means mounted on the mount for gripping the margin of the upper proximate to its toe end; means for moving the gripping means forwardly of the shoe support to stretch

the upper about the last; means for swinging the mount together with the shoe support and gripping means about the rod from a position remote from the lasting unit and the hold-down unit to a position adjacent thereto; means for actuating the powered means to raise the shoe support to thereby clamp the last and shoe between the shoe support and the hold-down foot; means for raising the gripping means upwardly of the shoe support to stretch the upper tightly on the last; means for moving the lasting unit forwardly from its out-of-the-way position to its working position; means to actuate the clamping means to clamp the heel portion of the upper against the last; means to move the wiping means forwardly across the insole to wipe the upper margin down upon the insole; and means operative concomitantly with the forward movement of the wiping means to raise the hold-down foot and cause the powered means to press the wiped upper margin against the bottom of the wiping means.

5. A shoe upper tensioning mechanism comprising: a rod; a last supporting means located at the upper end of the rod for supporting a last having a shoe upper and insole thereon; a block mounted on the rod below the last supporting means; bar means mounted on the block and extending forwardly thereof; an upper tensioning unit slidably mounted on the bar means for rectilinear movement toward and away from the block; normally open gripper means mounted on the upper tensioning unit; means for closing the gripper means to cause it to grip the margin of the upper; and means for thereafter causing the upper tensioning unit to move along the bar means away from the block to thereby stretch the upper about the last.

6. A shoe upper tensioning mechanism comprising: a rod; a last supporting means located at the upper end of the rod for supporting a last having a shoe upper and insole thereon; a block mounted on the rod below the last supporting means; bar means connected to said block and extending forwardly thereof; an upper tensioning unit slidably mounted on the bar means; at least one pincers located on said upper tensioning unit for gripping the margin of the upper; and motor means extending from the block to the upper tensioning unit for moving the upper tensioning unit along the bar means.

7. A shoe upper tensioning mechanism comprising: a rod; a last supporting means located at the upper end of the rod for supporting a last having a shoe upper and insole thereon; a block mounted on the rod below the last supporting means; bar means connected to said block and extending forwardly thereof; a block mounted on the rod below the last supporting means; a head slidably mounted on the bar means; a motor mounted on the block and connected to the head for moving the head along the bar means; a bar mounted on the head for movement in a direction substantially normal to the bar means; at least one pincers supported by the bar for gripping the shoe upper; and a motor mounted on the head and connected to the bar for effecting the movement of the bar and the pincers.

8. A shoe upper tensioning mechanism comprising: a rod; a last supporting means located at the upper end of the rod for supporting a last having a shoe upper and insole thereon; a block mounted on the rod below the last supporting means; at least one bar connected to the block and extending forwardly thereof; an upper tensioning unit slidably mounted on said bar; at least one pincers located on said upper tensioning unit for gripping the margin of the upper; a motor mounted on the block and connected to the upper tensioning unit to effect its movement; a shelf connected to said bar; a bracket movably mounted on the shelf; and control means interconnecting the bracket and motor, responsive to shifting of the bracket along the shelf, to actuate the motor means to move the upper tensioning unit on the bar an amount corresponding to the amount that the bracket is shifted along the shelf.

9. A shoe upper tensioning mechanism comprising: a rod; a last supporting means located at the upper end of the rod for supporting a last having a shoe upper and in-

sole thereon; a block mounted on the rod below the last supporting means; at least one bar connected to the block and extending forwardly thereof; an upper tensioning unit slidably mounted on said bar; at least one pincers located on said upper tensioning unit for gripping the margin of the upper; a fluid operated drive motor mounted on said block having a piston rod connected to said upper tensioning unit; a shelf connected to said bar; a bracket slidably mounted on the shelf; a fluid actuated pilot motor mounted on the bracket having a piston rod extending toward the block; means for normally actuating the pilot motor to project its piston rod toward the block; a pilot valve mounted on the upper tensioning unit between the pilot motor and the drive motor having a spool normally engaged by the pilot motor piston rod; and control means interconnecting the drive motor, the pilot motor and the pilot valve, responsive to shifting of the bracket along the shelf, to actuate the drive motor to move the upper tensioning unit along the bar an amount corresponding to the amount that the bracket is shifted along the shelf.

10. A shoe upper tensioning mechanism comprising: a rod; a last supporting means located at the upper end of the rod for supporting a last having a shoe upper and insole thereon; a block mounted on the rod below the last supporting means; at least one bar connected to the block and extending forwardly thereof; an upper tensioning unit slidably mounted on said bar; at least one pincers located on said upper tensioning unit for gripping the margin of the upper; a fluid operated drive motor mounted on said block having a piston rod connected to said upper tensioning unit; a bracket connected to said bar; a fluid actuated pilot motor mounted on said bracket having a piston rod extending toward the block; a pilot valve mounted on the upper tensioning unit between the pilot motor and the drive motor having a spool normally engaged by the pilot motor piston rod; means for normally supplying pressure fluid to the pilot motor to extend its piston rod toward the pilot valve spool; and control means interconnecting the drive motor, the pilot motor and the pilot valve, responsive to retraction of the pilot motor piston rod away from the pilot valve spool to actuate the drive motor to move the upper tensioning unit along the bar and thereby stretch the upper.

11. A shoe upper tensioning unit comprising: a head; a bar mounted in the head for heightwise movement, said bar having an upright limb and a prone leg extending away from the upper end of the upright limb on each side of the upright limb; a motor mounted in the head and connected to the bar for effecting heightwise movement of the bar; a front pincers mounted on the upright limb of the bar; a side pincers mounted on each prone leg of the bar; and a toe support mounted forwardly of the bar.

12. A shoe upper tensioning unit comprising: a head; a bar mounted in the head for heightwise movement, said bar having an upright limb and a prone leg extending away from the upper end of the upright limb on each side of the upright limb; a motor mounted in the head and connected to the bar for effecting its heightwise movement; a front pincers mounted on said upright limb; a bracket slidably mounted on each leg; a side pincers mounted on each bracket; and means to move the brackets on the bar legs toward or away from each other to thereby adjust the side pincers toward or away from each other.

13. A shoe upper tensioning mechanism comprising: a rod; a last supporting means located at the upper end of the rod for supporting bottom-up a last having a shoe upper and insole thereon; a block mounted on the rod below the last supporting means; at least one bar connected to the block and extending forwardly thereof; a head slidably mounted on said bar; a motor mounted on the block and connected to the head for effecting its movement along the bar; a toe support mounted in the head; a pincers supporting bar mounted in the head rearwardly of the toe support for heightwise movement; said pincers supporting bar having an upright limb and a prone leg extending away from the upper end of the upright limb

on each side of the upright limb; a motor mounted in the head and connected to the pincers supporting bar for effecting its heightwise movement; a front pincers mounted on said upright limb; a bracket slidably mounted on each leg; a side pincers mounted on each bracket; and means to move the brackets on the bar legs toward or away from each other to thereby adjust the side pincers toward or away from each other, said pincers being adapted to grip the margin of said upper.

14. A lasting machine comprising: a frame; wiping means mounted in the frame for movement in a predetermined plane; a post swingably mounted for movement about an axis parallel to said plane; means carried by the post for supporting a last having a shoe upper and insole thereon and for gripping the toe portion of the upper margin; a fluid actuated motor supported by the frame; and means interconnecting the motor and the post operative in response to actuation of the motor to swing the post so that the last and shoe are moved from a position remote from the wiping means to a position adjacent the wiping means.

15. A lasting machine comprising: a frame; wiping means mounted in the frame for movement in a predetermined plane; a hold-down foot located forwardly of the wiping means having its bottom located slightly below the bottom of the wiping means; a fluid actuated motor mounted in the frame below the wiping means; a piston rod extending upwardly of said motor; a post swingably mounted on said piston rod for movement about an axis parallel to said predetermined plane; means carried by the post for supporting bottom-up a last having a shoe upper and insole thereon and for gripping the upper margin proximate to its toe end; a second motor mounted in the frame; means interconnecting the second motor and the post operative in response to actuation of the second motor to swing the post so that the last and shoe are moved from a position remote from the wiping means to a position adjacent the wiping means; and means for actuating the first motor to raise the piston rod an amount sufficient to force the insole against the hold-down foot.

16. A lasting machine comprising: a frame; wiping means mounted in the frame for movement in a predetermined plane; a hold-down foot located forwardly of the wiping means having its bottom located slightly below the bottom of the wiping means; a fluid motor mounted in the frame below the wiping means; a piston rod extending upwardly of said motor; a post swingably mounted on said piston rod for movement about an axis parallel to said predetermined plane; means carried by the post for supporting bottom-up a last having a shoe upper and insole thereon and for gripping the upper margin proximate to its toe end; a second motor mounted in the frame; a support movably mounted in the frame and connected to said second motor to be moved thereby; link means interconnecting the support and the post to swing the post upon actuation of the second motor so that the last and shoe are moved from a position remote from the wiping means to a position adjacent the wiping means; and actuating means carried by the support actuatable towards the end of the support movement to activate the first motor to raise the piston rod an amount sufficient to force the insole against the hold-down foot.

17. A lasting machine comprising: a frame; wiping means mounted in the frame for movement in a predetermined plane; a hold-down foot located forwardly of the wiping means having a bottom slightly below the bottom of the wiping means; a first fluid actuated motor mounted in the frame below the wiping means; a first piston rod extending upwardly of said motor; a post swingably mounted on said first piston rod for movement about an axis parallel to said predetermined plane; means carried by the post for supporting bottom-up a last having a shoe upper and insole thereon and for gripping the upper margin proximate to its toe end; a second fluid actuated motor mounted in the frame; a second piston rod

extending from said second motor; a support movably mounted in said frame and connected to said second piston rod to be moved thereby; link means interconnecting said support and the post operative upon movement of the support through actuation of said second motor to swing the post so that the last and shoe are moved from a position remote from the wiping means to a position adjacent the wiping means; cooperative valve and valve actuating means mounted on the frame and support operative to actuate the valve means towards the end of the support movement; and means interconnecting the valve means and the first motor operative upon actuation of the valve means to activate the first motor to raise the first piston rod an amount sufficient to force the insole against the hold-down foot.

18. In a lasting machine: a shoe support for supporting a last having a shoe upper and insole thereon; a frame; a plate slidably mounted in the frame; wiping means connected to the plate for movement in unison therewith; a hold-down foot located above the shoe support with its bottom slightly below the bottom of the wiping means; means for raising the shoe support to bring the insole into engagement with the hold-down foot; means for thereafter advancing the plate from an out-of-the-way position relatively remote from the shoe support to a working position adjacent the shoe support while the wiping means remains immobile with respect to the plate; and means for thereafter advancing the wiping means forwardly relatively to the plate while the plate is stationary to wipe the upper margin upon the insole.

19. A machine as defined in claim 18 further comprising: a clamp mounted on the plate below the wiping means for movement in unison with the plate while the clamp remains immobile with respect to the plate; and means for advancing the clamp in relation to the plate to clamp the upper against the last while the plate is stationary and while the upper margin is being wiped by the wiping means.

20. In a lasting machine: a shoe support for supporting a last having a shoe upper and insole thereon; a frame; a plate slidably mounted in the frame; wiping means connected to the plate for movement in unison therewith; a hold-down foot located above the shoe support with its bottom slightly below the bottom of the wiping means; a motor mounted in the frame, means connecting the motor to the plate; means for raising the shoe support to bring the insole into engagement with the hold-down foot; means for thereafter actuating the motor to move the plate from an out-of-the-way position relatively remote from the shoe support to a working position adjacent the shoe support while the wiping means remains immobile with respect to the plate; and means for thereafter advancing the wiping means forwardly relative to the plate while the plate is stationary to wipe the upper margin upon the insole.

21. A machine as defined in claim 20 further comprising: a clamp mounted on the plate below the wiping means for movement in unison with the plate while the clamp remains immobile with respect to the plate; and means for advancing the clamp in relation to the plate to clamp the upper against the last while the plate is stationary and while the upper margin is being wiped by the wiping means.

22. In a lasting machine: a shoe support for supporting a last having a shoe upper and insole thereon; a frame; a plate slidably mounted in the frame; wiping means connected to the plate for movement in unison therewith; a hold-down foot located above the shoe support with its bottom slightly below the bottom of the wiping means; a motor, having a drive rod, mounted on the frame; a toggle linkage interconnecting the rod and the plate; means for raising the shoe support to bring the insole into engagement with the hold-down foot; means for thereafter actuating the motor to cause the rod to open the toggle linkage to move the plate from an out-of-the-way

position relatively remote from the shoe support to a working position adjacent the shoe support while the wiping means remains immobile with respect to the plate; and means for thereafter advancing the wiping means forwardly relative to the plate while the plate is stationary to wipe the upper margin upon the insole.

23. A machine as defined in claim 22 further comprising: a clamp mounted on the plate below the wiping means for movement in unison with the plate while the clamp remains immobile with respect to the plate; and means for advancing the clamp in relation to the plate to clamp the upper against the last while the plate is stationary and while the upper margin is being wiped by the wiping means.

24. In a lasting machine: a shoe support for supporting a last having a shoe upper and insole thereon; a frame; a plate slidably mounted in the frame; wiping means connected to the plate for movement in unison therewith; a hold-down foot located above the shoe support with its bottom slightly below the bottom of the wiping means; a bar depending from the plate; a fluid actuated motor, having a piston rod extending upwardly thereof, mounted on the bar; a block fixed in position relative to the frame; a first link and a second link, said links being pivotally connected at one end to the piston rod and being respectively pivotally connected at their opposite ends to the bar and block; means for raising the shoe support to bring the insole into engagement with the hold-down foot; means for thereafter actuating the motor to cause the piston rod to straighten the links and move the plate from an out-of-the-way position relatively remote from the shoe support to a working position adjacent the shoe support while the wiping means remains immobile with respect to the plate; and means for thereafter advancing the wiping means forwardly relative to the plate while the plate is stationary to wipe the upper margin upon the insole.

25. The apparatus according to claim 24 wherein means are provided for moving the block forwardly or rearwardly to thereby adjust the out-of-the-way position of the plate.

26. The apparatus according to claim 24 wherein the block is internally threaded, and a screw is rotatably mounted in the frame and screwed into the block, whereby rotation of the screw causes the block and the plate to move forwardly or rearwardly so that the out-of-the-way position of the plate may be adjusted.

27. A machine as defined in claim 24 further comprising: a clamp mounted on the plate below the wiping means for movement in unison with the plate while the clamp remains immobile with respect to the plate; and means for advancing the clamp in relation to the plate to clamp the upper against the last while the plate is stationary and while the upper margin is being wiped by the wiping means.

28. A lasting mechanism comprising: a frame; a wiper supporting plate slidably mounted in the frame for planar, rectilinear movement; a pair of wiper cams supported on said plate; a wiper connected to each wiper cam, said wipers being symmetrically disposed above said plate; means interconnecting each wiper cam and the plate permitting the wipers to move inwardly with respect to the plate; a drive rod mounted above said plate; link means connecting the rod to said wiper cams; a crank pin mounted to rotate about an axis transverse to the plane of movement of the plate; a slot in the wiper supporting plate receiving the crank pin; drive means connected to the drive rod operative to effect its forward movement; and means connecting the drive rod and the crank effective to rotate the crank upon forward movement of the drive rod.

29. The lasting mechanism according to claim 28 wherein the slot extends in a direction normal to the direction of movement of the plate.

30. A lasting mechanism comprising: a frame, a wiper

supporting plate slidably mounted in the frame for planar, rectilinear, forward and rearward movement; a pair of wiper cams supported on said plate; a wiper connected to each wiper cam, said wipers being symmetrically disposed above said plate; means interconnecting each wiper cam and the plate permitting the wipers to move inwardly with respect to the plate; a drive rod mounted for forward and rearward movement above said plate; a pair of links pivoted at one of their ends to the drive rod and pivoted at their other ends to the wiper cams; a rack on said drive bar; a pinion geared to said rack, rotatable about an axis transverse to the plane of movement of the plate; a crank pin eccentrically mounted on the pinion; and a slot in the plate in which the crank pin is received.

31. A lasting machine comprising: a shoe support for supporting a last having a shoe upper and insole thereon; a frame; a main plate mounted in the frame; a heel clamping means located forwardly of the main plate; clamp driving means mounted on the main plate and operatively connected to the heel clamping means to press the clamping means against the upper and last; a wiper supporting plate slidably mounted in the frame for forward and rearward movement above the main plate; a pair of wiper cams supported on the wiper supporting plate; a wiper mounted in each wiper cam, said wipers being symmetrically disposed with respect to the wiper supporting plate; means interconnecting the wiper cams and the wiper supporting plate permitting the wipers to move inwardly with respect to the wiper supporting plate; a motor mounted on the main plate; a drive element connected to the motor to be moved thereby upon actuation of the motor; and means interconnecting the drive element, the wiper supporting plate and the wipers, operative in response to the movement of the drive element, to move the wiper supporting plate and the wipers carried thereby forwardly and to move the wipers inwardly with respect to the wiper supporting plate to cause the wipers to wipe the upper margin upon the insole.

32. The lasting machine according to claim 31 wherein the main plate is slidably mounted in the frame, and further comprising: means to move the main plate together with the clamping means and the wipers supported by the main plate from an out-of-the-way position relatively remote from the shoe support to a working position adjacent the shoe support.

33. A lasting machine comprising: a shoe support for supporting a last having a shoe upper and insole thereon; a frame; a main plate mounted in the frame; a heel clamping means located forwardly of the main plate; clamp driving means mounted on the main plate and operatively connected to the heel clamping means to press the clamping means against the upper and last; a wiper supporting plate slidably mounted in the frame for forward and rearward movement above the main plate; a pair of wiper cams supported on the wiper supporting plate; a wiper mounted in each wiper cam, said wipers being symmetrically disposed with respect to the wiper supporting plate; means interconnecting the wiper cams and the wiper supporting plate permitting the wipers to move inwardly with respect to the wiper supporting plate; a fluid actuated motor mounted on the main plate rearwardly of the wiper cams; a bridge connected to the main plate intermediate the motor and the wiper cams and extending above the wiper supporting plate; a piston rod extending forwardly of the motor beneath the bridge; a pair of links extending from the piston rod to the wiper cams, each of said links being pivoted at one end to a wiper cam and pivoted at the other end to the piston rod; a rack on said piston rod; a pinion, rotatably mounted in the bridge, geared to the rack; a crank pin depending from the pinion and located eccentrically of the axis of rotation of the pinion; and a slot in the wiper supporting plate receiving the crank pin, whereby forward movement of the piston rod in response to actuation of the motor causes the wiper supporting plate and the wipers carried

thereby to move forwardly and causes the wipers to move inwardly with respect to the wiper supporting plate to enable the wipers to wipe the upper margin upon the insole.

5 34. The lasting machine according to claim 33 wherein the main plate is slidably mounted in the frame, and further comprising: means to move the main plate together with the clamping means and wipers supported by the main plate from an out-of-the-way position relatively remote from the shoe support to a working position adjacent the shoe support.

10 35. The lasting machine according to claim 34 further comprising: indicia means mounted on the frame; and a gauge bar connected to said bridge registerable with said indicia means.

15 36. In a lasting machine: a shoe support for supporting a last having a shoe upper and insole thereon; a frame; a plate slidably mounted in the frame; wiping means connected to the plate for movement in unison therewith; 20 means for advancing the wiping means forwardly relative to the plate to wipe the upper margin upon the insole; means for advancing the plate from an out-of-the-way position relatively remote from the shoe support to a working position adjacent the shoe support; indicia means mounted on the frame; and gauge means, registerable with the indicia means, connected to the plate for movement therewith.

25 37. A lasting machine comprising: wiping means mounted for forward movement; a shoe support adjacent the wiping means for supporting bottom-up a last having a shoe upper and insole thereon; a hold-down foot located above the shoe support with its bottom located slightly below the bottom of the wiping means; powered means operatively connected to the shoe support to apply an upward force thereto with the insole bearing exclusively against the hold-down foot; a first motor having a rod that is driven upon operation of the motor and which rod is operatively connected to the wiping means for moving the wiping means forwardly in a wiping stroke to wipe the upper margin down against the insole; a second motor operatively connected to the hold-down and operative upon actuation to raise the hold-down foot; a control member for actuating the second motor; and an actuating member on the rod for actuating the control member as the wiping means effect their wiping stroke to thereby raise the hold-down foot and cause the powered means to press the wiped upper margin against the bottom of the wiping means.

40 38. A lasting machine comprising: a frame; wiping means movably mounted in the frame for forward movement; a first fluid actuated motor having a first piston rod operatively connected to the wiping means to effect its forward movement; a lug on said first piston rod; a valve located in the path of movement of said lug; a second fluid actuated motor supported on the frame; a second piston rod extending upwardly of said second motor; a shoe support for supporting bottom-up a last having a shoe upper and insole thereon supported by said second piston rod; a hold-down foot located above the shoe support with its bottom normally slightly below the bottom 45 of the wiping means; a third fluid actuated motor having a third piston rod that is so connected with the hold-down foot as to normally maintain the hold-down foot in said normal position when the third piston rod is in one position and to raise said hold-down foot when the third piston rod is moved by the third motor to another position; means to actuate said second motor to raise said second piston rod and the shoe support carried thereby to press the insole exclusively against the hold-down foot; means to actuate said first motor to move the wipers forwardly 50 to wipe the upper margin against the insole and to cause the lug to engage the valve; and means responsive to engagement of the valve to actuate said third motor to move said third piston rod to raise the hold-down foot and cause the second motor to press the upper margin against the bottom of the wiping means.

39. A fluid motor control system comprising: a plurality of fluid actuated motors; a pilot valve; a spool movably mounted in the valve and having a first, a second and a third position in the valve; fluid flow control means interconnecting the valve and said motors; first spring means yieldably urging said spool to said first position; a stop aligned with said spool; second spring means yieldably urging said stop to a location that is determinative of the second position of the spool; means operative in response to movement of the spool from said first position to said third position with the spool engaging the stop and moving it against the force of the second spring means to enable said flow control means to operate said motors in seriatim in a predetermined sequence; and means operative in response to movement of the spool from said third position to said second position by said second spring means at any particular time before the termination of said sequence to stop the operation of said flow control means and cause the motors to maintain the posture they had assumed at that time.

40. A fluid motor control system comprising: a plurality of fluid actuated motors; a pilot valve having a housing and a spool movably mounted in the housing; said spool having a first, a second and a third position in the housing; fluid flow control means interconnecting the valve and said motors; a first spring interposed between the spool and housing yieldably urging the spool to said first position; a bracket; a stud slidably mounted in said bracket; a second spring interposed between said stud and bracket yieldably urging said stud to a location that is determinative of the second position of the spool; means operative in response to movement of the spool from said first position to said third position, with the spool overcoming the force of the first spring, engaging the stud, and moving the stud against the force of the second spring to enable the flow control means to operate said motors in seriatim in a predetermined sequence; and means operative in response to movement of said spool from said third position to said second position by said second spring, at any particular time before the termination of said sequence, to stop the operation of said flow control means and cause the motors to maintain the posture they had assumed at that time.

41. A shoe upper stretching and heel seat lasting machine comprising: wiper means mounted for forward movement; a hold-down located forwardly of the wiper means; a mount; a shoe support located on the mount and positioned below the hold-down and forwardly of and below the wiper means for supporting bottom-up a last having a shoe upper mounted thereon and an insole located on its bottom with the heel of the last facing the wiper means; gripping means mounted on the mount and located forwardly of the shoe support for gripping the margin of the upper proximate to its toe end; means for moving the gripping means forwardly of the shoe support to stretch the upper about the heel of the last; means for thereafter raising the gripping means upwardly of the shoe support to stretch the upper tightly on the last; means for imparting relative closing movement between the shoe support and the hold-down prior to the raising of the gripping means to rigidly clamp the last and shoe between the shoe support and the hold-down; and means for thereafter imparting forward movement to the wiper means to wipe the heel portion of the margin of the upper against the insole.

42. A shoe upper stretching and heel seat lasting machine comprising: wiper means mounted for forward movement; a hold-down located forwardly of the wiper means; a mount; a shoe support located on the mount and positioned below the hold-down and forwardly of and below the wiper means for supporting bottom-up a last having a shoe mounted thereon and an insole located on its bottom with the heel of the last facing the wiper means; gripping means mounted on the mount and located forwardly of the shoe support for gripping the margin of the upper proximate to its toe end; means for moving the

gripping means forwardly of the shoe support to stretch the upper about the heel of the last; means for thereafter imparting relative closing movement between the shoe support and the hold-down to rigidly clamp the last and shoe between the shoe support and the hold-down; means for thereafter raising the gripping means upwardly of the shoe support to stretch the upper tightly on the last; and means for thereafter imparting forward movement to the wiper means to wipe the heel portion of the margin of the upper against the insole.

43. A shoe upper tensioning mechanism comprising: a rod; a last supporting means located at the upper end of the rod for supporting a last having a shoe upper and insole thereon; a block mounted on the rod below the last supporting means; at least one bar connected to the block and extending forwardly thereof; an upper tensioning slidably mounted on said bar; at least one pincers located on said upper tensioning unit for gripping the margin of the upper; a fluid actuated drive motor mounted on said block and having a piston rod connected to said upper tensioning unit; a shelf connected to said bar; a bracket slidably mounted on the shelf; a fluid actuated pilot motor mounted on the bracket, said pilot motor having a movable piston rod; means for normally actuating the pilot motor to project its piston rod outwardly thereof; a pilot valve mounted on the upper tensioning unit having a spool normally engaged by the pilot motor piston rod; and control means interconnecting the drive motor, the pilot motor and the pilot member, responsive to shifting of the bracket along the shelf, to actuate the drive motor to move the upper tensioning unit along the bar an amount corresponding to the amount that the bracket is shifted along the shelf.

44. A shoe upper tensioning mechanism comprising: a rod; a last supporting means located at the upper end of the rod for supporting a last having a shoe upper and insole thereon; a block mounted on the rod below the last supporting means; at least one bar connected to the block and extending forwardly thereof; an upper tensioning unit slidably mounted on said bar; at least one pincers located on said upper tensioning unit for gripping the margin of the upper; a fluid actuated drive motor mounted on said block having a piston rod connected to said upper tensioning unit; a bracket connected to said bar; a fluid actuated pilot motor mounted on said bracket, said pilot motor having a movable piston rod; a pilot valve mounted on the upper tensioning unit having a spool normally engaged by the pilot motor piston rod; means for normally supplying pressure fluid to the pilot motor to extend its piston rod toward the pilot valve spool; and control means interconnecting the drive motor, the pilot motor and the pilot valve, responsive to retraction of the pilot valve piston rod away from the pilot valve spool, to actuate the drive motor to move the upper tensioning unit along the bar and thereby stretch the upper.
